Inventor
C. O. Noack.

By his Attorney *C. P. Goepel*

UNITED STATES PATENT OFFICE.

CARL O. NOACK, OF STAMFORD, CONNECTICUT.

FOLDING TYPEWRITER.

1,403,810.

Specification of Letters Patent. Patented Jan. 17, 1922.

Application filed March 21, 1921. Serial No. 453,863.

To all whom it may concern:

Be it known that I, CARL O. NOACK, a citizen of the United States, and resident of Stamford, county of Fairfield, and State of Connecticut, have invented new and useful Improvements in Folding Typewriters, of which the following is a specification.

This invention relates to folding typewriters and particularly to a typewriter of 10 that general construction illustrated and described in Patent No. 1,284,714 granted to Edward Krusius, on November 12, 1918.

It is the primary object and purpose of the present invention to provide an improved lever actuated back spacing mechanism for a machine of the above type, which will permit of the folding of the keyboard carrying frame upon which the back space lever is mounted, while at the same time providing for absolute accuracy and reliability in the operation of the back space mechanism.

It is also one of the detail objects of the invention to provide simple and effective 25 means whereby wear and lost motion consequent to the operation thereof may be compensated for so that the proper operation of the several cooperating parts is at all times assured.

With the above and other objects in view, the invention consists in the improved form, construction and relative arrangement of the several parts as will be hereinafter more 35 fully described, illustrated in the accompanying drawings and subsequently incorporated in the subjoined claims.

In the drawings wherein I have illustrated one satisfactory and desirable embodiment of the invention and in which 40 similar reference characters designate corresponding parts throughout the several views:

Figure 1 is a top plan view of a part of the frame structure of the machine, showing the 45 back spacing mechanism thereof and the lever operated connections;

Figure 2 is a longitudinal section taken on the line 2—2 of Figure 1;

Figure 3 is a section taken on the line 3—3 50 of Figure 1; and

Figure 4 is a section taken on the line 4—4 of Figure 1.

The main frame 5 and the keyboard carrying frame 6 of the machine are similar in 55 construction, mounting and arrangement to the corresponding parts shown and de-

scribed in a co-pending application Serial No. 453,862 for patent on folding typewriters filed of even date herewith. It will accordingly be understood that the frame 60 section 6 is adapted to be folded from an extended horizontal position in advance of the frame section 5 to a substantially vertical inoperative position. The invention forming the subject matter of the present application 65 is more particularly concerned with the means whereby the back space lever mounted upon the keyboard carrying frame 6 is operatively connected with and disconnected from the actuating means for the back spacing mechanism, which is mounted and arranged upon the rear side of the main frame 5. Therefore, I have herein shown only those parts of the machine structure which are necessary to a clear understanding of the 70 present invention. As illustrated in the accompanying drawings, the back space lever 7 is pivotally mounted intermediate of its ends as at 8 upon the pivoted foldable frame section 6. The forwardly extending portion 70 of this lever is movable in a vertical slot 9 in the front portion of the frame section 6 and a spring 10 disposed in said slot urges the lever upwardly to its normal position. The portion of the lever extending rearwardly from the pivot 8 is formed with a plurality of angularly offset sections so that the rear end 11 of said back space lever is located a considerable distance inwardly 85 from the side of the frame and adjacent to the center thereof.

The back spacing mechanism for the platen carriage which is mounted upon the rear side of the frame section 5 may be of any ordinary or approved type. As herein 90 shown this mechanism includes the pinion 12 which is in constant mesh with the teeth of a rack 12' fixed to the carriage 13. A ratchet 14 is fixed upon the shaft of the pinion 11 and with this ratchet the pawl or dog 15 engages. This pawl is pivoted at its lower side, as shown at 16, upon the bracket 17.

Upon the under side of the machine frame section 5 the rock shaft 18 is journaled in suitable bearings 19 and the oscillating 105 movement of this rock shaft in one direction is resisted by the coil spring 20. The rear end of said rock shaft is formed with the angularly extending arm 21, which is operatively connected by means of the link 22 to 110 the pawl 15.

Upon the forward end of the rock shaft 18

a plate 23 is fixed, said plate extending upon relatively opposite sides of said shaft. This plate is provided adjacent to its opposite ends with the slots 24. One end of an arm 25 is angularly offset as at 26 and this end portion 26 of the arm is loosely engaged upon the rock shaft 18 at the inner side of the plate 23. Screws 27 are engaged through the slots 24 in the plate 23 and are threaded 10 in the end portion of the arm 25.

This arm extends laterally from one side of the shaft 18 and above the plane of said shaft and overlies the rear end 11 of the back space lever 7. Preferably, though not necessarily, the lower edge of this arm is curved as shown. The return movement of the rock shaft 18 under the action of the spring 20 to its normal position is limited 15 by the adjustable stop screw 28 with which 20 the pawl 15 engages.

From the above description it will be seen that when the keyboard carrying frame section 6 is in its horizontal operative position, the rear end of the back space lever 7 is engaged with the lower edge of the arm 25. Thus when the key lever 7 is depressed at its forward end the rear end thereof is elevated so that it cooperates with the arm 25 to rock the shaft 18, thus imparting movement to 30 the pawl 15 through the link connection 22, which in turn co-acts with the ratchet 14 to rotate the pinion 11 and move the platen carriage backwardly one step. Upon the release of the lever 7 it is returned to its normal position by the spring 10 and the spring 35 20 then returns the parts of the actuating means for the back spacing mechanism to their normal positions as seen in Figure 3 and the arm 25 is maintained in engagement 40 with the upper edge of the lever end 11. When the machine is to be folded and enclosed within its carrying case, the keyboard carrying frame section 6 is lifted or raised to a substantially vertical position as shown 45 in my companion application and the lever end 11 will, therefore, be moved forwardly and away from the lower edge of the arm 25. However, immediately upon the return of the frame section 6 to its operative position, 50 the operating engagement between the back space lever and the arm 25 is automatically re-established.

By the provision of the adjusting means 55 27 for the arm 25, wear of the contacting edges of this arm and the lever end 11 may be compensated for and lost motion thus eliminated so as to insure at all times the necessary extent of movement of the parts to properly operate the back spacing mechanism.

It will be understood that my present invention is of general application to foldable typewriting machines wherein the keyboard carrying frame section is foldable into compact relation with the main frame of the

machine and is not necessarily limited to the particular pivotal connection between the two frame sections or by the specific locking means for the foldable frame section as disclosed in my companion application for patent hereinbefore referred to. 70

In the foregoing description I have referred to an embodiment of the invention which I have found to give very satisfactory results in practical use. It will nevertheless be understood that various mechanical alterations may be resorted to in adapting the present device to various makes of foldable typewriting machines. Accordingly, I reserve the privilege of adopting all such legitimate changes in the form, proportion, and relative arrangement of the several parts as may be fairly embodied within the spirit and scope of the invention as claimed. 75

I claim:

1. In combination with a typewriter having a keyboard carrying frame foldable with respect to the main frame, and a back spacing mechanism on the main frame; means for actuating the back spacing mechanism including a rock shaft mounted in the main frame and operatively connected at one end to the back spacing mechanism, a back space lever mounted in the keyboard carrying frame and an arm connected to the other end of said rock shaft and overlying the rear end of said back space lever. 85

2. In combination with a typewriter having a keyboard carrying frame foldable with respect to the main frame, and a back spacing mechanism on the main frame; means for actuating the back spacing mechanism including a rock shaft mounted in the main frame and operatively connected at one end to the back spacing mechanism, a back space lever mounted in the keyboard carrying frame, an arm connected to the other end of the rock shaft and overlying the rear end of the back space lever and means for angularly adjusting said arm with respect to the lever. 100

3. In combination with a typewriter having a keyboard carrying frame foldable with respect to the main frame, and a back spacing mechanism on the main frame; means for actuating the back spacing mechanism including a rock shaft mounted in the main frame and operatively connected at one end to the back spacing mechanism, a back space lever mounted in the keyboard carrying frame, a plate fixed upon the other end of the rock shaft, an arm loosely engaged upon the rock shaft and overlying the rear end of the back space lever and means for adjustably securing said arm to said plate, 115 whereby the angular relation of the arm with respect to the lever may be changed. 120

4. In combination with a typewriter having a keyboard carrying frame foldable with respect to the main frame, and a back 130

spacing mechanism on the main frame; means for actuating the back spacing mechanism including a rock shaft mounted in the main frame and operatively connected 5 at one end to the back spacing mechanism, a back space lever mounted in the keyboard carrying frame, a plate fixed upon the other end of the rock shaft, an arm extending at right angles to the back space lever and overlying the rear end thereof, and means for 10 adjustably securing said arm to said plate to change the angular relation of the arm with respect to said lever.

5. In combination with a typewriter having a keyboard carrying frame foldable with respect to the main frame, and a back spacing mechanism on the main frame; means for actuating the back spacing mecha-

nism including a rock shaft mounted in the main frame and operatively connected at one 20 end to the back spacing mechanism, a back space lever mounted in the keyboard carrying frame, a plate fixed to the other end of said rock shaft and extending upon opposite sides thereof, said plate having a slot 25 therein on each side of the rock shaft, an arm loosely engaged upon the rock shaft and overlying the rear end of the back space lever and means fixed to the arm and movable in said slots for adjustably securing 30 the arm of said plate in the desired angular relation with respect to the back space lever.

In testimony that I claim the foregoing as my invention, I have signed my name hereunder.

CARL O. NOACK.
